UNITED STATES PATENT OFFICE.

WILLIAM E. BRYANT, ROBERT DAVIDSON, AND GEORGE M. WOLCOTT, OF DETROIT, MICHIGAN, ASSIGNORS TO MICHIGAN LUBRICATOR COMPANY, OF DETROIT, MICHIGAN, A CORPORATION.

VISIBLE AUXILIARY OILER FOR LUBRICATORS.

SPECIFICATION forming part of Letters Patent No. 783,717, dated February 28, 1905.

Application filed August 4, 1904. Serial No. 219,474.

To all whom it may concern:

Be it known that we, WILLIAM E. BRYANT, ROBERT DAVIDSON, and GEORGE M. WOLCOTT, citizens of the United States, residing at Detroit, in the county of Wayne, State of Michigan, have invented certain new and useful Improvements in Visible Auxiliary Oilers for Lubricators; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to condensation-displacement sight-feed lubricators; and it consists in providing such a lubricator with an automatic auxiliary oiler through the medium of which oil may be supplied to the parts of the lubricator by way of the sight-feed chamber of the regular oil-feed.

The object of the invention is to provide a lubricator of the character described with an auxiliary oiler which shall be automatic in its operation and in which the arrangement is such as to enable the oil to be drawn from the supply within the reservoir and discharged through the sight-feed chamber, whereby the quantity of oil fed may be discerned and regulated according to the requirements, as distinguished from the ordinary hand-oilers commonly employed.

The common practice in the employment of auxiliary oilers upon lubricators of this class is to provide an open hand-oiler, which may be used in cases of emergency and which is filled by hand and the contents discharged at once into the tallow-pipe for the purpose of lubricating the valves of the steam-chest and the piston in the cylinder. This process is necessarily slow and awkward, and by its use the distribution of oil is very irregular, nor is it possible with this arrangement to see the quantity of oil that is passing from the auxiliary oiler to the parts to be lubricated. By means of the arrangement herein shown an automatic auxiliary oiler is provided which re-

quires no separate sight-feed glass, but which is made to feed through the sight-feed chamber 50 of the regular feed, obviating the employment of extra parts and at the same time enabling the operator to readily see the quantity of oil which is being fed. The means by which this result is obtained are illustrated in 55 the accompanying drawings, in which—

Figure 1 is an elevation of a lubricator embodying our invention, parts being in section or broken away. Fig. 2 is an exaggerated view, in sectional detail, showing the auxiliary 60 oil-passage leading from the reservoir to the sight-feed chamber and controlled by a screw plug-valve. Fig. 3 is an enlarged sectional view through the condenser, the central sight-feed chamber, and the top of the reservoir as 65 taken on line 3 3 of Fig. 1.

Referring to the characters of reference, 1 designates the body of the lubricator, in which is situated the oil-reservoir 2. Mounted upon the body of the lubricator are the sight-feed 70 features 3, containing the observation-glasses 4 of the bull's-eye type, there being within each of said sight-feed features an observation-chamber 5, the ends of which are closed by said glasses. The sight-feed features are 75 connected to the top of the lubricator-body by the stems 6, which are formed integral with said body. Mounted upon the central sight-feed feature is the condenser 7, whose interior is connected with the reservoir by a cored passage-way 8, which passes downwardly through the stem 6 and communicates with the upper end of the tube 9, which depends within the reservoir, whereby the water of condensation is conveyed from the condenser to the bottom of 85 the reservoir of the lubricator, the flow of water through said passage-way being controlled by the valve 10. Extending through the condenser into the steam-pipe 11 is a stand-pipe 12, whose lower end communicates with a cored 90 passage (indicated by dotted lines 13 in Fig. 3) leading to a caliduct or steam-chamber 14 within the reservoir, at the top thereof, and from which lead the equalizing-passages 15, (see Fig. 2,) passing vertically through the 95 sight-feed features and communicating with

the oil-discharge ports 16, with which the upper ends of the tallow-pipes 17 are connected, all of which is more fully set forth in a copending application, Serial No. 219,475. 1 Formed through the stem of each of the sight-feed features is an oil-feed passage-way 18, controlled by the feed-valve 19 and having at the upper end thereof a feed-nozzle 20, which projects into the sight-chamber 5 and 10 from which the oil ascends in drops through the water in said chamber and out the discharge-port 16 to the tallow-pipe, as will be well understood.

For the purpose of supplying an auxiliary oiler to be used when the ordinary feed becomes stopped or is rendered inoperative from any cause an auxiliary oil-feed passage 21 is formed through the stem of the sight-feed feature which connects the top of the reservoir with the sight-feed chamber 5, said passage being controlled by a plug-valve 22, adapted to be turned by the application of a wrench. Should it be desired to employ the auxiliary oiler, it is only necessary to turn the plug-valve 22 so as to open the passage-way 21, when the oil by hydrostatic pressure will be caused to flow upwardly from the reservoir through said passage-way into the sight-chamber and through said chamber between the observation-glasses to the discharge-port 16. The oil which ascends through said passage-way is rendered visible through the observation-glasses, and the quantity may be regulated by an adjustment of the valve 22, whereby the flow may be maintained as constant as though the regular feed were in operation. By this arrangement an accident to the regular feed does not impair the efficiency of the lubricator, and by passing the oil from the auxiliary through the regular sight-feed the engineer is able to see the amount of oil which is being fed from the reservoir, so that the feeding of an excessive quantity of oil may be obviated and the flow of lubricant regulated in accordance with the requirements.

Communicating with the sight-chamber is a passage-way 23, controlled by a valve 24, having a hollow stem, by means of which the water may be drawn out of the sight-chamber from between the glasses when desired.

Having thus fully set forth our invention, what we claim as new, and desire to secure by Letters Patent, is—

1. In a lubricator, the combination with the condenser and oil-reservoir, of a sight-feed chamber having an observation-glass therein through which the passage of the oil may be observed, said chamber having the usual con-

nection with the reservoir, there being a substantially vertical oil passage-way connecting the reservoir directly with the bottom of said chamber independently of the regular connection through which substantially vertical passage-way oil may be directed past the observation-glass of the regular sight-feed feature. 65

2. In a lubricator, the combination with the condenser and oil-reservoir, of a sight-feed feature mounted upon the top of the reservoir having a sight-chamber therein, observation-glasses in the ends of said chamber, there being the regular oil-feed passage-way connecting the reservoir with said chamber and there being an auxiliary oil passage-way also connecting the reservoir with said chamber, whereby the oil delivered through said auxiliary oil 75 passage-way will pass between the observation-glasses of the sight-feed chamber.

3. In a lubricator, the combination with the condenser and oil-reservoir, of a sight-feed feature having an observation-chamber with a glass therein and the usual connection with said reservoir, there being an auxiliary feed passage-way connecting said sight-feed feature with the reservoir independently of the regular connection arranged to direct the oil 85 through the sight-feed chamber by way of said auxiliary instead of through the regular oil passage-way.

4. In a lubricator, the combination with the condenser and oil-reservoir, of a sight-feed 90 feature mounted upon the top of the reservoir, a sight-feed chamber in said feature, opposed glasses arranged within said chamber, there being an auxiliary oil passage-way leading directly from the top of the reservoir into the 95 lower part of said chamber at a point between said glasses, whereby the oil delivered from the auxiliary passage-way may be observed through the regular sight-feed glass.

5. In a lubricator, the combination with the condenser and oil-reservoir, of a sight-feed feature, said sight-feed feature having an observation-chamber therein provided with the usual connection with the reservoir, and also having an auxiliary feed connection with the 105 reservoir communicating with the bottom of and discharging through said chamber independently of said usual connection.

In testimony whereof we sign this specification in the presence of two witnesses.

WILLIAM E. BRYANT.

ROBERT DAVIDSON.

GEORGE M. WOLCOTT.
